(57) CLAIM

The ornamental design for a hooded garment, as shown and described.

DESCRIPTION

FIG. 1 is a front left perspective view of a hooded garment showing my new design in an in-use configuration with a hood in an up position;

FIG. 2 is a front right perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The broken lines in immediately adjacent to the shaded area represent unclaimed boundaries of the design. The unshaded regions, demarcated by broken lines, represent unclaimed portions of the hooded garment and form no part of the claimed design. The contrast in shading represents a contrast in appearance only and does not represent any particular color, material, texture or finish. The broken lines showing the remainder of the hooded garment are for environmental purposes only and form no part of the claimed design.
